STAND FOR BICYCLES

Frank W. Schwinn, Chicago, Ill.

Application April 10, 1944, Serial No. 530,286

2 Claims. (Cl. 280—301)

The present invention relates to stands for bicycles, and is particularly concerned with stands of the type usually termed "kick-stands," due to the fact that it may be moved into or out of its operative position by a kick of the user.

In the kick-stands of the prior art, with which I am familiar, the working parts are generally exposed to the elements with resultant rapid wear. Due to this fact and the fact that they cannot be lubricated without gathering dust and dirt, this accumulation of dust and dirt accelerates the wear because the combination of the dust and dirt with the oil acts as an abrasive.

When such a device of the prior art has been lubricated, the dust and dirt on the lubricated parts presents a situation in which the mechanism looks very unsightly and there is always the possibility of the dust, dirt, and oil getting on the clothing of the user; and as a result, the user dispense with lubrication. This also results in rapid wear, and increases the friction involved in the movement of the stand from one position to another, so that the rider may resort to drastic action, such as violent kicking in the use of the device, which also serves to shorten its useful life.

Another disadvantage of the devices of the prior art is that the cam in such devices will eventually work loose in the housing, and when this occurs the assembly will rattle.

One of the objects of the present invention is the provision of an improved kick-stand for bicycles that is so constructed that the wear on the cam in the housing will be automatically taken up and the cam will be held in tight, non-rattling engagement with its housing at all times by the spring of the device.

Another object of the invention is the provision of an improved kick-stand for bicycles in which the mechanism is suitably enclosed so that it is protected from exposure to the elements and so that it may be suitably lubricated without gathering dust and dirt on the exterior of the assembly.

Another object of the invention is the provision of a kick-stand which is adapted to be maintained in a well lubricated condition without having the lubricant leak out and cover the exterior of the housing so as to eliminate any possibility of dust and dirt getting into the mechanism, or of having the exterior parts of the mechanism covered with lubricant, which would gather dust or dirt.

Another object of the invention is the provision of a device of the class described which is simple, sturdy, and capable of being manufactured at a

low cost, so that it may be placed within the means of a vast number of users.

Another object of the invention is the provision of an improved construction for kick-stands which can be manufactured for sale as a separate accessory, or which may be incorporated as a permanent part of the bicycle.

Another object of the invention is the provision of an improved kick-stand which is adapted to be held firmly in its operative position and which may be moved from either one or the other of its positions with a minimum amount of effort.

Other objects and advantages of the invention will be apparent from the following description and the accompanying drawings, in which similar characters of reference indicate similar parts throughout the several views.

Referring to the drawings, of which there are two sheets,

Fig. 1 is a fragmentary sectional view, taken on a vertical plane passing through the lower part of the bicycle frame at right angles to the plane of the frame, showing a kick-stand attached to the frame embodying the present invention and supporting the bicycle in approximately vertical position;

Fig. 2 is a fragmentary top plan view, with the kick-stand shown in full lines in its folded or inoperative position, and shown in dotted lines in its extended or operative position;

Fig. 3 is a fragmentary side elevational view of the bicycle frame and kick-stand, with the crank shaft and bearings removed and the stand in the folded position;

Fig. 4 is a fragmentary sectional view, taken on the plane of the line 4—4 of Fig. 2;

Fig. 5 is a fragmentary sectional view, taken on the plane of the line 5—5 of Fig. 4, looking in the direction of the arrows;

Fig. 6 is a fragmentary sectional view of the cam and housing, similar to Fig. 4, on an enlarged scale;

Fig. 7 is a fragmentary sectional view, taken on the plane of the line 7—7 of Fig. 6, looking in the direction of the arrows;

Fig. 8 is a fragmentary elevational view, showing the end of the kick-stand housing from the right of Fig. 6;

Fig. 9 is an end elevational view of the cam; and

Fig. 10 is a fragmentary sectional view, taken on the same plane as Fig. 1, showing a modified mode of attachment of the kick-stand housing to the bicycle frame.

Referring to Figs. 1 to 3, 30 indicates in its entirety a bicycle frame, part of which is shown to

illustrate the application of the invention to a bicycle. The frame portion shown includes the crank shaft bearing hanger 31, which is integrally attached to the lower rear fork members 32, 33 and to the upwardly extending frame member 34, which usually ends in a saddle post, and to the forwardly extending frame member 35.

The kick-stand is indicated in its entirety by the numeral 36, and it preferably includes a housing member 37 and the usual prop member or sprag 38, which is movably supported by the housing 37 for movement into the inoperative or folded position.

The inoperative or folded position is shown in full lines in Fig. 2, and the operative or extended position is shown in full lines in Fig. 1.

The housing 37 comprises a tubular metal member, which is preferably substantially cylindrical and preferably constructed of steel, having a cylindrical wall portion 39 over the major portion of its length. At its right end in Fig. 4 this housing has a tapered portion 40, which is triangular in elevation, and preferably provided with sides of equal length.

The three sides of this triangular portion are indicated at 41-43 (Fig. 8), and the cylindrical wall 39 tapers down toward the triangular end portion 40. Thus the sides 41-43 have a curved outline 44 at their inner ends, corresponding to the shape of this section of a cylinder. The tapered end portion 40 of the housing is, of course, also similarly tapered on its inside, and it has a substantial fit with the cam member 45, which is adapted to be held against rotation by reason of its similar non-circular shape.

In order that the cam member 45 may have adequate room for taking up wear in the housing portion 40, this housing portion is formed with a clearance at 46 on the inside, this clearance effectively extending the cylindrical chamber 47 of the housing so that as the external surface of the cam wears it may move axially of the housing 37 and be kept in constant tight engagement with the non-circular end portion 40. The cam body is constantly urged into its socket by the spring, but may be worn by rattling action of the vehicle or by the stress that is placed upon it as the pin moves from one slot to the other tending to rotate the cam body. Any such exterior wear between the socket for the cam body and the exterior of the cam body may be taken up by further movement of the cam body into its socket.

The right end 48 of the housing is open, but it is closed by the end wall 49 of the cam 45. The cam 45 comprises a metal member preferably made of steel, having a cylindrical wall portion 50 and a tapered wall portion 51, which is triangular in cross section. This makes the end wall 49 of reduced size, and the triangular end portion 51 of the cam 45 is preferably substantially complementary to the inside of the housing 37.

The exterior of the cam is thus provided with partially cylindrical corner formations 52, and the inside of the corners of the housing portion 40 is also complementarily curved at 53.

The cam member 45 is preferably hollow, having an inner cylindrical bore 54 for receiving the end portion of the stand trunnion 55. The edges of the end of this cam are shown in Fig. 9, and this edge portion is formed with two sets of diametrically extending grooves.

The grooves 56, 57 are for the reception of the pin 58 when the sprag is in the folded or inop-

erative position, while the grooves 59, 60 receive this pin 58 when the sprag is in the operative position, as shown in Fig. 1.

The grooves 56, 57, 59, 60 are partially cylindrical in shape, and preferably slightly more shallow than half a cylinder.

Thus, when the sprag is rotated, the pin 58 is adapted to ride up out of the groove in which it happens to be, and over the flat surfaces 61 until 10 the pin drops in the opposite groove.

The segmental portions 62 of the cam may extend axially farther than the portions 61, since the pin is not intended to ride up over the surfaces 62; but in some embodiments of the invention these surfaces may be located in the same plane.

The sprag 38 preferably includes the trunnion portion 55, the prop portion 63, and a foot portion 64. The length of the prop portion 63 is 20 preferably such that when the bicycle is supported on the sprag its frame extends upward at a slight angle so that the weight of the frame and other parts rest upon the kick-stand.

This involves making the prop portion 63 25 shorter than the distance from its housing to the ground by an amount which is indicated by the dotted line position shown in Fig. 1, where the frame is in vertical position, and the sprag does not touch the ground.

30 The foot portion 64 merely comprises a laterally bent end portion of the sprag for engaging the ground and locating the point of engagement farther from the center of gravity of the bicycle in the lateral direction.

35 The sprag is preferably made of a cylindrical rod of metal, such as steel; and the angular bends at 65 and 66 in this rod are preferably less than the right angle, as shown, so that the strut portion 63 is also used to extend the sprag laterally 40 so that its foot will be in engagement with the ground at a point to the left of the center of gravity of the frame in Fig. 1.

45 Adjacent its right end the trunnion portion 55 of the sprag is provided with a bore 67 for receiving the pin 58. The pin 58 is a cylindrical steel pin, which may have a sliding fit in the bore 67, or it may have a tight frictional fit.

The pin 58 is preferably engaged by a washer 68, which is rectangular in cross section and fits 50 between the inside of the housing 37 and the trunnion portion 55. The washer 68 is engaged by a compression spring 69 of helical form, which is preferably thick enough to fill the space between the trunnion portion 55 and the cylindrical wall 55 39 of the housing 37.

55 Thus the spring serves to provide additional bearing for the trunnion portion 55 when supported by the housing 37. In order to provide a bearing for the trunnion 55, the housing 37 has 60 at its left end a bearing 70.

This comprises an annular metal member, the outer cylindrical wall 71 of which fits in the housing 37, and the inner bore 72 of which has a rotating fit with the trunnion 55. A bore 73 may 65 be drilled through the housing wall 39 and the bearing 70, and may be provided with a cotter-pin 74 for holding the bearing 70 in fixed position.

The spring 69 reacts against the inner end of the bearing 70 and urges the sprag toward the right in its housing 37.

The housing 37 in the case of a permanent installation is preferably welded as at 75 to the lower rear fork members 32, 33 in such position that it extends rearwardly toward the left side 75 of the frame. This permits the sprag 38 to fold

up under the rear fork member 33, when it is in its inoperative position.

In another embodiment of the invention the housing 37 may be provided with a sheet metal bracket 76, having a pair of partially cylindrical portions 77, 78, which fit against the lower inside of the rear fork members 32, 33.

These partially cylindrical portions 77, 78 are joined by a flat web 79, and a similar bracket member 80 is placed on the upper side of the rear fork member 32, 33 and held in place by the threaded member 81.

The bracket 76 is welded to the housing 37 at 82, and has its web 79 provided with a nut 83 registering with the aperture 84. The upper bracket has another aperture 85, and the threaded member 81 comprises a bolt which passes through the aperture 85 and is threaded into the nut 83.

The bolt 81 preferably has an elongated head 86 so that a wrench may engage its head because 20 the head projects from the bracket 80.

The annular shoulder 87 on the head 86 clamps the two brackets 80, 76 together and secures the housing to the two rear fork members.

The operation of the present kick-stand is as follows: The spring 69 constantly urges the pin 58 toward the right in Fig. 4 into engagement with the cam 45, and when the pin 58 is in one of the pairs of grooves 59, 60 or 56, 57 the spring will hold the sprag in that position.

The weight which is placed upon the sprag by the frame tends to drive the pin into engagement with its grooves still more tightly; and thus there is no tendency of the sprag to be rotated out of its operative position by the weight of the vehicle.

When the sprag is turned from its operative position to the inoperative position, or vice versa, the pin 58 cams against the side of the groove in which it happens to be, and the pin rides up 40 on the flat surfaces 61, permitting the sprag to rotate until the pin drops into the other groove. There it is held by the spring 69 until the operator again moves the sprag to another position.

The present housing may be filled with thick grease, which keeps the mechanism lubricated at all times and excludes dust and dirt. As the housing is closed at both ends, the grease is kept in the housing, and the dust and dirt are kept outside.

The cam and the spring provide additional bearing surface for the trunnion of the sprag, and as the cam becomes worn in any way it is driven still further into its complementary non-circular tapered socket to take up this wear. Thus rattling is prevented, and the present device may be used for a long period of time without experiencing the objectionable rattling or wear or deterioration found in the devices of the prior art.

While I have illustrated a preferred embodiment of my invention, many modifications may be made without departing from the spirit of the invention, and I do not wish to be limited to the precise details of construction set forth, but 65 desire to avail myself of all changes within the scope of the appended claims.

Having thus described my invention, what I claim as new and desire to secure by Letters Patent of the United States is:

1. In a bicycle kick stand, the combination of a tubular metal body formed of substantially cylindrical shape forming a bearing, the end of said body being deformed to provide an outwardly tapered, non-circular formation on its inside, a prop member comprising a cylindrical rod having its lower end outwardly bent in one direction at an obtuse angle to form a foot and having its upper end bent in the opposite direction at an obtuse angle to form a trunnion, the said trunnion being rotatably mounted in said tubular member, a bearing at the cylindrical end of said tubular member fixedly secured to said tubular member for rotatably supporting said trunnion, and a helical spring member, the coils of which are of sufficient thickness to bridge the space between the trunnion and the interior of said tubular member to give the trunnion additional bearing support, the said spring engaging a thrust washer, and said thrust washer engaging a transverse pin carried by said trunnion adjacent its end, a cam member of tapering, non-circular shape complementary to the interior surface of the tapered end of said tubular member, said cam member having at its inner end depressions in two positions for receiving the pin and holding the prop in its bicycle supporting and in its folded position.

2. In a bicycle kick stand, the combination of a tubular metal body formed of substantially cylindrical shape forming a bearing, the end of said body being deformed to provide an outwardly tapered, non-circular formation on its inside, a prop member comprising a cylindrical rod having its lower end outwardly bent in one direction at an obtuse angle to form a foot and having its upper end bent in the opposite direction at an obtuse angle to form a trunnion, the said trunnion being rotatably mounted in said tubular member, a bearing at the cylindrical end of said tubular member fixedly secured to said tubular member for rotatably supporting said trunnion, and a helical spring member, the coils of which are of sufficient thickness to bridge the space between the trunnion and the interior of said tubular member to give the trunnion additional bearing support, the said spring engaging a thrust washer, and said thrust washer engaging a transverse pin carried by said trunnion adjacent its end, a cam member of tapering, non-circular shape complementary to the interior surface of the tapered end of said tubular member, said cam member having at its inner end depressions in two positions for receiving the pin and holding the prop in its bicycle supporting and in its folded position, the said cam also comprising a hollow member of substantially triangular shape at its closed outer end and having a cylindrical shape at its inner end receiving the end of said trunnion for additional bearing support.

FRANK W. SCHWINN.
